SYMMETRICAL BUOYANT VEST

Edgar G. Baker, Carbondale, Pa., assignor to General
Corporation, New York, N.Y., a corporation of
Delaware

Filed Mar. 21, 1967, Ser. No. 6,318

Term of patent 14 years

(Cl. D71—1)

FIGURE 1 is a front elevational view of a buoyant vest, showing my new design, the rear view thereof being a mirror image thereof.

FIGURE 2 is a right side elevational view thereof, the left side thereof being a mirror image thereof.

FIGURE 3 is a top plan view thereof, with dot-dash elements removed for purposes of clarity.

FIGURE 4 is a bottom plan view thereof, with dot-dash elements removed for purposes of clarity.

The portions shown in dot-dash lines and broken away are for purposes of illustration only.

I claim:

The ornamental design for a symmetrical buoyant vest, substantially as shown and described.
